216,296

PACKAGE OF PAPER TOWELS AND HOLDER THEREFOR

George Victor Skowronski, Neenah, Wis., assignor to American Can Company, New York, N.Y., a corporation of New Jersey

Filed June 17, 1968, Ser. No. 12,376

Term of patent 14 years

Int. Cl. D9—04

U.S. Cl. D9—193

FIG. 1

The bottom is plain and unornamented.

I claim:

The ornamental design for a package of paper towels and holder therefor, as shown and described.
